UNITED STATES PATENT OFFICE.

THOMAS A. WESTON, OF STAMFORD, CONNECTICUT, ASSIGNOR TO THE YALE & TOWNE MANUFACTURING COMPANY, OF SAME PLACE.

HOISTING-MACHINE.

SPECIFICATION forming part of Letters Patent No. 320,315, dated June 16, 1885.

Application filed December 21, 1883. (No model.)

To all whom it may concern:

Be it known that I, THOMAS A. WESTON, of Stamford, in the county of Fairfield and State of Connecticut, have invented certain new and useful Improvements in Hoisting Mechanisms, of which the following is a specification, reference being had to the accompanying drawings, in which--

Figure 1 is a front elevation of a hoisting-machine, partly in section. Fig. 2 is an elevation of one end of the same, drawn to a larger scale, and showing a lever mechanism applied to it. Fig. 3 is a section on the line 3 3 of Fig. 2. Figs. 4 and 5 are to illustrate the invention upon which my present invention is an improvement and to aid in giving an idea of my present invention. Fig. 6 is a view similar to Fig. 2, differing, formally, in showing the stud and groove transposed. Fig. 7 is a section on the line 7 7 of Fig. 6. Fig. 8 is a central longitudinal section of a simple winding-drum with my improvements applied to it. Figs. 9 and 10 are similar views showing slight, merely formal, modifications.

My present invention being mainly based upon the one for which a United States patent was issued to me December 14, 1869, No. 98,000, I will, in order that it may be better understood, first briefly describe the 1869 invention illustrated by Figs. 4 and 5 of the accompanying drawings, which figures are taken from Figs. 3 and 4 of the patent drawings. That invention consists in providing the toothed driving-pinion of a hoisting-machine with a frictional device whereby the rotation of the shaft in one direction effects the clutching of the pinion and its detached ratchet-wheel frictionally to the shaft for the purpose of hoisting. The contrary rotation of the shaft, so long as it is maintained, effects the lowering of the load. At all times, whether in hoisting or lowering, if the handle be let go, or if the driving of the shaft suddenly cease, the load will not run away, because of the automatic self-arresting action of the frictional mechanism, the construction and operation of which I will now describe, as it is arranged according to the above-named patent.

In Fig. 4, 1 is the driving-shaft of a hoisting-crab or like machine, having securely fixed

to it the incline-faced collar 2, and also the plain flange or collar 3. Between them, and thereby confined longitudinally upon the shaft, are the loose ratchet-wheel 4 and the pinion 5. The ratchet-wheel has frictional contact on one side with the plain shaft-collar, on the other with the pinion side. The pinion has its boss or center next the incline-faced collar formed with an inclined face, as shown in Fig. 5, and the contiguous face of the incline-faced collar is correspondingly shaped—that is to say, having a helical or screw-formed face curved spirally around the axial line of the shaft. The pinion-teeth engage with a main driving-wheel and drum for lifting a load in the usual manner. Such load tends to resist motion in the drum, spur-wheel, and engaged pinion 5, and to hold them at rest. Rotary motion for hoisting being applied to the shaft 1 in a direction to carry the incline 70 of the collar 2 to ascend the incline of the pinion 5, the pinion is crowded or forced against the ratchet-wheel and the ratchet-wheel against the flange 3. When all loose motion is taken up and the pinion 5 can yield 75 no farther in a longitudinal direction, the collar 2 pushes before it in its rotation the pinion, and by friction upon its sides the ratchet-wheel also. The severe end-thrusts of the inclines effectually unite by friction all the said 80 parts, so that any load may be thus lifted, the said frictional adhesion always increasing with the increasing weight of a heavier load. Upon ceasing to hoist the ratchet-wheel 4 is checked from backward rotation by a pawl, and with 85 it also the pinion and all connected parts, through the frictional hold of the pinion side, and also of the plain flange upon the ratchet-wheel between them. Upon turning the shaft backward in a direction to release the inclines 90 or unscrew them from each other, the frictional hold upon the now stationary ratchet-wheel is reduced or removed; but as this is done the pull of the load causes the pinion and its incline to follow closely, and thus continually to 95 restore the said frictional connection of the parts. The load may thus be lowered, as desired, by continuing the backward rotation of the shaft.

In my said invention of 1869 the incline- 100

faced collar of the shaft prevented the pinion and gearing driven thereby from being closely placed to the hoist-frame, as is often desirable. The inclines were not readily adjustable to 5 each other as to the play or loose motion between them. The shaft, having to be turned backward when lowering, was incapable of having affixed to it permanently for ready use a supplementary driver—such as a band-pulley and band always in place, or a power-driven spur-wheel always in gear with its driving pinion—and the ratchet-wheel was, of necessity, placed the next pinion, involving a stationary attachment to the frame at this point 15 for supporting a pawl in an exposed place where its accidental disengagement and the fall of the load might readily occur. All these objections are by my present invention removed, and several additional advantages at 20 the same time secured.

The present invention consists in its leading feature in making one or both of the helical inclines upon a tubular sleeve or sleeves, as and for the purposes hereinafter explained.

25 Referring to the letters on the accompanying drawings, A, Figs. 1, 2, 3, 6, and 7, indicates the hoist-frame; B, the main spur-wheel with attached drum B'. C is a loose pinion, and D its shaft. E is a driving-wheel loose 30 upon the shaft D, with crank-handle for hoisting and lowering. F is a plain driving wheel and crank for hoisting only, and by preference replaced by the improved ratchet-lever (shown in Figs. 2, 3, 6, and 7) for heavy loads, requiring 35 higher mechanical power than is furnished by the driver E or F. G may be a plain collar or flange of the shaft; but preferably it is a brake-box containing the frictional disks of my Patent No. 75,227 of March 40 3, 1868, or any suitable friction-brake for simply augmenting the frictional adhesion between the pinion C and the shaft. H is an internally-toothed ratchet-wheel fixed to the shaft D, and having a vertical bolt or pawl, I, 45 sliding within a slot in the hoist-frame. The crank-wheel or driver E and the pinion C being loose upon the shaft, can rotate thereon freely between the screw-nut D', collar or washer D', and the disk-box G, the latter being 50 fixed to the shaft. The driver E has its boss E' provided with a helical or inclined face to act upon a corresponding incline, C', formed by the end of the tube or sleeve C, which is an integral part of the pinion C. The 55 said inclines act substantially with each other and the connected parts as explained in my aforesaid Patent No. 98,000 of 1869—that is to say, when the driver E is rotated in the direction of the arrow the inclines effect a coupling 60 action or frictional engagement between the pinion C, collar or disk box G, and the shaft for the duty of hoisting, and a contrary motion continually releases the said frictional connection to effect the lowering of a load. In 65 this latter or lowering motion, however, the shaft D is held at rest by the ratchet-wheel and pawl H I.

As the part of this my present invention next in importance, I affix permanently to the shaft D, in lieu of the plain driver F, an improved ratchet-lever, K, Figs. 2, 3, 6, and 7, of a length or radius much greater than that of the crank-handle of the wheel E to furnish a larger purchase for lifting the heaviest loads. As the shaft D has no backward motion, the 70 long ratchet-lever K' needs no disengagement therefrom, but remains at rest, held in any desired normal position by the coiled spring O, Figs. 2, 3, 6, and 7, always ready for instant use. 80

The advantages of giving to the inclines or helices the tubular or sleeve form of my present invention are various. For example, first, the inclines are conveniently adjustable to each other by the screw-nut D', exterior to the 85 frame and accessible; second, compactness is obtained by allowing the pinion C to be placed close to the hoist-frame, and convenience by allowing the ratchet-wheel H to be at any desired position along the shaft, preferably next 90 to the hoist-frame, as shown; third, the absence of all backward motion of the shaft D permits the permanent attachment of a very long and powerful ratchet-lever or other driving device for lifting heavy loads; fourth, the 95 tubular construction of the inclines or helices permits the driver or part operating one incline to be at any desired distance from the driven part carrying the other incline simply by an elongation of the tube or sleeve, enabling 100 the said parts to be separated by a bearing, as in Fig. 1, for the convenience of placing the driver E on one side of the said bearing or frame and the driven pinion C on the other side, when required. 105

In place of an ordinary ratchet-wheel and pawl I employ the improved form shown in Figs. 1, 2, 3, 6, and 7. The pawl I cannot be accidentally thrown out; but it may be released, if desired, by pushing upward its 110 lower counter-weighted end, I', which should be of such weight as to insure a prompt falling action. The pawl I slides in a groove or vertical recess cast for it in the frame. Its acting end and the ratchet-wheel teeth are 115 securely covered within the wheel from dirt and injury.

The details of the ratchet-teeth, pawls, springs, and other parts of the lever K K', Figs. 2, 3, 6 and 7, are substantially those of 120 my United States Patent No. 212,336. In addition thereto the lever K has a stud, L, on it vibrating in a circular groove or slot, M, in the boss N of the hoist-frame, to limit its arc of motion as desired, and a coiled spring, O, 125 to continually restore the lever to its normal position after use. The spring has its ends bent and entered into holes, one in the boss at P, the other in the lever at R. The stud may be on the boss and the groove in the lever K, 130 as shown in Fig. 2, if desired. S is the four-toothed ratchet-wheel of the lever K. It is fixed by the screw S' to the shaft D. The four teeth of ratchet-wheel S engage, differentially,

with the three sliding pawls T of the lever K, all constructed in accordance with the specification of my aforesaid Patent No. 212,336. The ratchet details or head of the lever K' may form the boss or center of a power-driven spur-wheel, the lever part K' and spring O being omitted, this arrangement thus affording the means of using supplementary driving power without involving the necessity for disconnecting the said supplemental gear when it is desired to operate the shaft D by hand through the driver E. An ordinary ratchet-wheel and pawl may be employed in place of the improved device K; but the latter I prefer for its compactness and efficiency.

It is obvious that the ratchet device of the supplemental driver permits the latter to be at rest while the shaft is driven from the opposite end by the driver E, the ratchet-pawls of lever K allowing the shaft to slip and turn in the direction of the arrow, Figs. 1 and 2.

The object of the screw-nut D' and collar D² is to furnish a frictional abutment for the boss of the driver E. It is desirable that the said abutment have more frictional hold upon or adhesion to the boss of E than that subsisting between the two incline surfaces E' C², to meet the case of the driving-power being exclusively applied at the other end of the shaft—that is to say, directly to the shaft D, by the driver F, or its lever substitute in Figs. 2 and 3, 6 and 7. In such case the coupling action of the inclines or their ascending movement upon each other can only occur by the frictional driving action of the collar D² rotating with it the driver E and its incline E', the latter thus advancing upon the other incline of the pinion C until its resistance and the load be overcome through the resulting frictional connection of the pinion and shaft D, effected within the friction box G. In the machine shown in Fig. 1 this excess of friction at D² is obtained simply by excess of diameter in the collar D² over the diameter of the incline surfaces E' C²; but it can be otherwise obtained or increased as, for example, by giving a cone form to the collar D² and a corresponding conical recess to the contiguous face of the boss or wheel E; or, by adding to the said contiguous faces or parts frictional disks, as is done within the box G. The disk-box G may be a plain enlarged collar upon the shaft; but the additional area of friction due to the disks renders the backward or lowering motion of the machine easy, and reduces the strain and wear of the moving parts.

Although I have described my invention in its primary application to hoisting mechanism, it is obviously applicable also where the pinion C and wheel B are operative parts of other machines requiring like driving and lowering mechanism. For instance, the pinion C may engage with the teeth of a rack-bar—such as employed in baling-presses—to force up the platen of the press; or the pinion C may operate the gearing of a stump-puller, and in various similar situations the

described driving and releasing or lowering motions of my inventions are usefully and generally applicable for applying multiplied mechanical force and safely withdrawing it.

It is essential to the operation of my safety frictional inclines that the driven incline be incapable of itself becoming the driver under the impulse of the load, and thus driving backward the other incline. In such case the load would run down. This is prevented in my inventions by so constructing the parts that the oblique thrust of the incline longitudinal to the shaft always creates an excess of retarding friction upon parts stationary in lowering—such as the ratchet-wheel and its attachments. It is also desirable in some cases that the driven incline have some retarding friction, that it may not be pushed around the shaft without being simultaneously pushed endwise thereon, in order to frictionally couple the various parts of the device. Both of these desired results are rendered more certain by this feature of my present invention—viz., in giving to the said inclines a tubular sleeve form, as further illustrated by Figs. 8 and 9.

Fig. 8 is a plain winding-drum provided with my improvements. B' is the drum. D is the shaft. E is the driving-wheel, having a sleeve with the incline at its end in contact with the corresponding incline of the drum. The drum and driver are both loose upon the shaft, and can turn freely thereon; but are confined longitudinally between the fixed collar E³ and the ratchet-wheel H, also fixed to the shaft. The latter has its face next the drum enlarged for frictional brake action therewith. X X' are ordinary bearings. A pawl (not shown) arrests all backward motion in the ratchet-wheel H. The sleeve of the driving-wheel supported in the bearing X is pressed thereon by a full share of the incumbent weight of the shaft D and all carried by it, yielding a proportionate frictional resistance upon the bearing to the rotation thereon of the sleeve. The said friction upon the exterior of the sleeve, together with the added friction of the shaft upon its interior, and that of the sleeve end or outer boss of the driver E against the collar E³, all unite in resisting the backward driving of the incline of the sleeve of the driving-wheel by the mere face-friction thereon of the other incline of the drum from the pull of the load upon the drum. Any rotary motion, therefore, on the drum-incline from the load simply advances it upon the retarded sleeve-incline, simultaneously thrusting the drum against the now stationary ratchet-wheel H, at once arresting its own motion by friction thereon. The friction upon all the parts named is obviously constant, always increased proportionately to an increase of weight in the load. The automatic braking action of my before-named original patented invention is made still more certain and convenient by the sleeve construction of the inclines described.

Fig. 9 illustrates the application of the sleeve

to a driven incline forming a portion of a small winch for oyster dredging, and fully described in my Letters Patent of the United States, No. 217,031, July 1, 1879. The shaft D is the driver, 5 carrying fixed to it the incline collar a, and also fixed to it the ratchet-wheel H and friction-flange b. The drum B' and incline collar d are detached from each other, and both are loose upon the shaft. The incline collar d has 10 cast upon it a ratchet-wheel, H², and also a sleeve, the latter embraced within and sustaining the adjacent end of the drum B'. A common pawl (not shown) always checks any back motion in the ratchet-wheel H. Another pawl, 15 (not shown,) capable of being readily thrown out of engagement, is provided for the ratchet-wheel H². The drum B' is capable of a free running-away motion when the pawl of the ratchet-wheel H² is thrown into engagement therewith to check its backward rotation along 20 with the drum. The said rapid backward or lowering motion is effected by turning backward a little the shaft D, so as to withdraw its incline from the other incline, releasing the 25 frictional coupling action of the inclines. The forward turning of the shaft at once retards or wholly arrests the said running-down movement of the drum by again advancing the incline a upon the other incline of the collar d, 30 held stationary by the pawl of the ratchet-wheel H². The self arrested or safety-lowering action of the inclines is obtained in Fig. 9 when the pawl of the ratchet-wheel H² is thrown back out of action and the shaft D turned steadily backward. The ratchet-wheel 35 H² then moves with the drum by means of its frictional contact with the adjacent drum end, the same as if fixed thereto. The said frictional adhesion of the ratchet-wheel and incline to the drum is further insured by the sleeve forming part of the said ratchet-wheel, receiving the weight of the drum B', and sustaining it, as shown in Fig. 9. Without the 40 said sleeve, however, any grooving of the shaft D by wear or corrosion at the part occupied by the ratchet-wheel H² might obstruct its free sliding motion up against the drum B', in which case the driving-incline a would push around before it on the shaft the said part without at 45 the same time pushing it along the shaft and against the drum B'. Thus the inclines would simply rotate together, neither one ascending the other, and the drum B' would remain at rest unaffected by the turning of the shaft D 50 and inclines. Such contingency I avert by the sleeve being always under the weight of the drum and load thereon. The retarding fric-

tion upon the sleeve insures its being held momentarily at rest, while the driven incline a ascends it, and thus effects the frictional connection of the moving parts, as described. 60

Fig. 10 illustrates the inclines, each formed upon a sleeve the parts of which meet midway on the bearing X². Each part of the sleeve thus receives a share of the load upon the shaft 65 and a due amount of retarding friction to insure the ascent of one incline upon the other, whichever may be first moved. Thus the sudden driving of the wheel E, the drum B' being unloaded, or the sudden addition of a load upon the drum, would alike carry one of the inclines upward upon the other and stationary one, and alike insure the automatic brake action of my invention. 70

What I claim, and desire to secure by Letters Patent, is—

1. In a hoisting-machine, one or more sleeves combined with and serving as a bearing for a shaft and provided with one or more frictional inclines, substantially as described. 80

2. The combination, with a shaft of a hoisting-machine, of a loose sleeve and a loose driver, both of which are provided with helical inclines, substantially as described.

3. In a hoisting-machine, the combination 85 of a main driving-shaft, a loose wheel or pinion thereon provided with an elongated sleeve having a helical incline, a driver having a boss with a corresponding incline, whereby the driver and engaging frictional inclines can be 90 placed outside of the supporting-frame of the machine, substantially as described.

4. In a hoisting-machine, the combination 95 of a main driving-shaft and two independent driving mechanisms constructed and arranged so that both or either will turn the shaft for hoisting, which shaft always remains stationary during the operation of lowering, substantially as described.

5. The combination of the shaft D, a retaining ratchet-wheel, and an operating ratchet-lever provided with a spring, O, substantially 100 as described.

6. The combination of the shaft D with an internally-toothed ratchet-wheel, H, and externally counter-weighted pawl I I', substantially as described. 105

In testimony whereof I have hereunto subscribed my name this 22d day of November, A. D. 1883.

THOS. A. WESTON.
